(57) **CLAIM**

The ornamental design for an electronic cigarette, as shown and described.

DESCRIPTION

FIG. 1 is a front elevation view of an electronic cigarette showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a right, front perspective view thereof.

The lightened part of the photograph shown in a coarser dot pattern within the broken-line perimeter, illustrates a portion of the electronic cigarette that forms no part of the claimed design.
